UNITED STATES PATENT OFFICE.

WILLIAM N. BEARDSLEY, OF BRIDGEPORT, CONNECTICUT.

DESIGN FOR A BICYCLE TOE-CLIP.

SPECIFICATION forming part of Design No. 26,488, dated January 5, 1897.

Application filed March 28, 1896. Serial No. 585,287. Term of patent 3½ years.

To all whom it may concern:

Be it known that I, WILLIAM N. BEARDSLEY, a citizen of the United States, residing at Bridgeport, in the county of Fairfield and 5 State of Connecticut, have invented and produced a new and original Design for Bicycle Toe-Clips; and I do declare the following to be a full, clear, and exact description of the same, reference being had to the accompanying drawings, forming a part thereof.

Figure 1 is a perspective view of the toe-clip, and Fig. 2 is a front end elevation looking in the direction of arrow *a* of Fig. 1.

The leading features of my design reside in 5 the concave sides of the shank *E* and the overhanging lip *F* and the diamond-shaped termination of said lip; also, the heart and

star shaped openings *H* and *G* in the said lip, combined with the elongated transverse openings *A*, *B*, and *C* in the end wall *D*, the central opening *A* being larger than the openings *B* and *C*, the whole producing an effect of lightness without detracting from the strength of the clip. 20

I claim—

The design for a bicycle toe-clip, substantially as herein shown and described.

In testimony whereof I affix my signature in presence of two witnesses.

WILLIAM N. BEARDSLEY.

Witnesses:

LEON WM. BEARDSLEY,
L. M. SLADE.
